UNITED STATES PATENT OFFICE

2,503,762

WATER FILLING NOZZLE

Emmet W. Narramore, Oakland, Calif.

Application September 30, 1946, Serial No. 700,312

2 Claims. (Cl. 226—129)

1

The present invention relates to a nozzle for filling the water tanks of railway passenger cars.

Standard railroad practice involves hoses attached to water hydrants at stations and car service yards, said hoses being left lying on the ground alongside the tracks when not in use. The end of each hose is provided with a nozzle adapted for temporary connection with the filling spouts of the car tanks.

One object of the present invention is to provide an improved nozzle which can be easily and quickly connected to, and detached from, the various types of car filling spouts in current use.

Other objects are to provide a nozzle that will remain clean and free from dirt, which will have long life, and which has only one part subject to wear, which can be easily renewed.

Still further objects and advantages of the invention will be apparent from the following description, which should be read with the understanding that changes, within the scope of the claims hereto appended, may be made in the form, construction and arrangement of the several parts, without departing from the spirit of the invention, as defined in said claims.

Reference will be made to the accompanying drawings, wherein

Fig. 1 is a part sectional elevation showing a filling hose equipped with my improved nozzle connected with a standard filling spout of a car having overhead water tanks.

Fig. 2 is a part sectional elevation of the same connected with one standard type of filling spout of a car having under-floor tanks.

Fig. 3 is a part sectional elevation of the same connected with another standard type of filling spout for under-floor tanks.

Fig. 4 is a longitudinal section, enlarged, of my improved nozzle.

Fig. 5 is an elevation of the end of the filling hose with my nozzle thereon, as it appears when lying on the ground.

In the drawings, the reference numeral 6 designates a portion of a railroad car having a water tank. In Fig. 1 the tank, not shown, is overhead, or high up in the car or on the roof, and is filled through a pipe 7, the lower end of which is attached to the frame of the car near the side by means of an elbow fitting 8, and which has a downwardly extended filling spout 9 provided with a tapered outer surface.

In Fig. 2, the water tank is shown at 10 under the floor of the car, and is filled through a pipe 11 terminating in a box-like filling spout 12 secured beneath the floor near one side of the car,

2

and said spout 12 has an aperture 13 in its outer wall. A suitable closure, not shown, is understood to be provided for the aperture 13.

In Fig. 3, the under-floor tank 10 and filling spout 12 are the same as in Fig. 2, except that the filling aperture 14 is smaller than the aperture 13 of Fig. 2. The three filling spouts shown at 9 in Fig. 1 and 12 in Figs. 2 and 3 are typical of those in current use on railroad passenger cars.

10 A portion of a flexible hose is shown at 15, said hose being attached to a water supply hydrant, not shown, in proximity to the track at a station or car service yard. The outer end of the hose 15 has a shut-off valve 16, from which extends a 15 short nipple 17 of rigid pipe. A circular guard plate 18 is secured to the nipple 17 to prevent the latter from coming in contact with the ground when the end of the hose is dropped, as shown in Fig. 5.

20 So much is standard equipment in current use. A short length of flexible hose, not shown, is commonly slipped over the end of the nipple 17, and left thereon, to connect it with the filling spout 9. Such short length of hose, being flexible, bends down and frequently becomes dirty by contact with the ground, and such dirt is washed into the car tank and contaminates the water therein.

25 My improved nozzle comprises a rigid tubular fitting 19 having an interior thread 20 at one end, and tapering outwardly to a larger diameter at its other or outer end. The threaded end 20 is screwed on the nipple 17. The larger outer end of the fitting 19 is provided with an annular interior groove 21 in which is seated a rubber gasket 22 of L-shaped cross section, as shown in Fig. 4. The interior diameter of the gasket 22 is such as to enable it to fit snugly around the filling spout 9 of the overhead tank, as shown in Fig. 1, and to maintain therewith a joint tight enough to stand the pressure necessary to raise the water into the overhead tank.

30 The outside diameter of the fitting 19 enables it to be inserted through the aperture 13 of the filling spout 12 of the under-floor tank shown in Fig. 2. However, when a filling spout is encountered which has a small aperture, as shown at 14 in Fig. 3, a short nipple of rigid pipe 23 is inserted in the end of said fitting 19 and frictionally held by the gasket 22, as shown in Figs. 3 and 5. This rigid nipple 23 is small enough in diameter to pass through the aperture 14.

35 It will be seen that my improved nozzle, whether the fitting 19 be used alone or with the additional nipple 23, is a rigid structure, rigidly

connected with the pipe nipple 17 and shut-off valve 16, so that all parts of it are held in the air by the guard disk 18, and no part can bend down into contact with the ground to be soiled thereby. Connecting the nozzle to or disconnecting it from any of the standard filling spouts shown is a simple and instantaneous operation, consisting of merely pushing it on or pulling it off the spout 9 of Fig. 1, or inserting it into or pulling it out of the filling apertures 13 or 14 of Figs. 2 or 3.

The fitting 19 is permanently attached to the pipe nipple 17, and being metal, lasts indefinitely. The only part subject to wear is the rubber gasket 22, which can be quickly replaced when worn.

I claim:

1. Means for filling railroad car water tanks comprising a water supply hose, a valve fitting at the free end thereof, a rigid pipe nipple extending from said valve, a rigid tubular nozzle having one end threaded upon said nipple, the axes of said nipple and said nozzle extending in a straight line, a flexible annular gasket mounted within the other end of said nozzle, and a substantially circular rigid guard surrounding and secured to said nipple in a plane at right angles to the axis thereof, said guard being so positioned lengthwise of said nipple that the weight on the

valve side of said guard exceeds the weight on the nozzle side thereof.

2. Means for filling railroad car water tanks comprising a water supply hose, a manually operated valve having a handle at the free end of said hose, a rigid tubular nozzle having one end connected with said valve, the axes of said valve and said nozzle extending in a straight line, a flexible annular gasket mounted within the other end of said nozzle, a substantially circular rigid guard mounted between said nozzle and said valve in a plane at right angles to the axes thereof, the radial distance from the line of said axes to the periphery of said guard being greater than the greatest distance from said axial line to any part of said valve including its handle, and said guard being so positioned that the weight on the valve side thereof exceeds the weight on the nozzle side.
